METHOD OF END LASTING

Jacob S. Kamborian, West Newton, Mass. (% International Shoe Machine Corp., 292 Main St., Cambridge, Mass.)

Filed July 9, 1958, Ser. No. 747,443

5 Claims. (Cl. 12—145)

This invention relates to the lasting of footwear, more especially to end lasting, and is especially directed to a method of end lasting in which adhesive is employed to attach the margin of an upper to an insole.

The customary way of end lasting with adhesive is to stress the upper heightwise of the last bottom in a toe lasting machine of the type shown, for example in Patent No. 2,668,967, wipe the margin inwardly to conform the upper to the shoulder, partially retract the wipers without releasing the upper, fold the margin back, that is, outwardly, daub adhesive on the margin of the folded back upper with a brush and then wipe the upper inwardly against the bottom. In Patent No. 2,614,527, there is shown a container provided with a nozzle for use with a lasting machine of the foregoing kind, to apply adhesive to the area of the insole at the toe, the nozzle being shaped to fit the area and containing a U-shaped orifice, so arranged as to distribute the adhesive uniformly over the surface at the toe. Another way of applying the adhesive is to use a spray gun or similar device for atomizing the adhesive and to spray it forcibly against the exposed margin. Such methods have proved unsuccessful, either because not enough adhesive was applied in the first place or if enough was applied it was squeezed out during the lasting process so that not enough remained to hold the lasting margin against the retractive stresses of the upper. As a consequence the bond has not been strong enough or tenacious enough to withstand the effects of time, temperature and pressure incident to the subsequent operations of drying, pounding, leveling and roughing in making the bottom ready for the sole attaching operation and wear.

It is the primary purpose of this invention to provide a novel method of attaching the lasting margin, at the end of a shoe, exclusively with thermoplastic adhesive, in such fashion as to produce a permanent bond which will hold the uplasting stress and hence snugness and sharpness of the upper at the shoulder of the last, which will endure throughout the roughing, pounding and bottom cementing operations subsequent thereto, which will not require for its formation any more time than is used in ordinary lasting practice, which will not fail by creep throughout the life of the shoe at ordinary temperatures and pressures expected to be encountered both in shoe manufacturing and during wear, which will not require any more than ordinary skill in its practice and which will not add to the expense of the manufacturing process as a whole.

As herein illustrated, the method of end lasting comprises assembling an insole and upper on a last, preliminary uplasting the upper so as to stress the lasting margin perpendicular to the bottom, holding the upper under stress at the shoulder of the last, folding the marginal edge outwardly, while thus held, to expose the junction between the inner surface of the upper and the insole, laying a continuous uniform ribbon of hot thermoplastic adhesive entirely around the end proximate to the junction and then wiping the entire margin inwardly against the bottom under a pressure perpendicular to the

2

bottom. In accordance with good shoe making practice after the initial upwiping stresses have been applied and before the margin is turned outwardly the margin is wiped inwardly over the bottom to conform the upper to the shoulder, the pulling over tacks are removed, if upstanding, and then after the margin is turned outwardly the excess marginal material, if any, including the box toe and lining material, if the latter is used, is trimmed. The final wiping of the lasting margin against the bottom is accomplished with one or more passes of the wiper. It is desirable to apply the adhesive in the form of an extruded "ribbon" of round cross-section, having a diameter in the order of about $\frac{1}{32}$ ", a viscosity of 150 poises at a temperature in the order of 120° to 134° C. and a melting point in the order of 95° to 115° C.

The invention will now be described in greater detail with reference to the accompanying drawing wherein:

Fig. 1 is a perspective of a last with an insole and upper assembled thereon, temporarily attached thereto by tacks; 20 Fig. 2 is a vertical section through an apparatus for conditioning the toe prior to lasting;

Fig. 3 is a fragmentary plan view at the toe showing the wipers embracing the shoulder of the last just below the surface of the insole, with the lasting margin folded back and with a continuous ribbon of adhesive applied along the angle between the margin and the insole;

Fig. 4 is a fragmentary vertical section to much larger scale showing the ribbon of adhesive in cross-section as applied in the angle between the lasting margin and the insole and in dotted lines its change of shape as the lasting margin is laid down against the insole;

Fig. 5 is a plan view of the completely lasted end;

Fig. 6 is an elevation diagrammatically showing the toe support and wipers of a lasting machine and an applicator mounted thereon for supplying adhesive;

Fig. 7 is a plan view at the toe showing an applicator for applying the adhesive into two symmetrical lengths; and

Fig. 8 is a plan view of a crescent shaped nozzle for applying a continuous ribbon of adhesive about the toe.

Referring to the drawing, there is shown in Fig. 1, a last 10, arranged bottom side up with an insole 12 attached to the bottom and an upper 14 pulled over the last and temporarily attached thereto, with its lasting margin extending upwardly beyond the bottom of the last, by means of a plurality of appropriately placed pulling over tacks 16. The assembled bottoms and uppers, as shown in Fig. 1, are prepared ahead of time and racked for the toe laster. Before commencing the lasting operation several

50 assemblies are placed in a steam box 18, as shown in Fig. 2, or other suitable means for conditioning the upper material and when a suitable time has elapsed they are removed one at a time from the conditioning apparatus and lasted on a toe lasting machine of the type shown, for example in my Patent No. 2,668,967, modified for simplicity of control, as shown in the pending application of Thomas A. Weisz, Control for Lasting Machine, Serial No. 563,270, filed February 3, 1956, now Patent No. 2,888,693, granted June 2, 1959. When properly located in the aforesaid machine with the toe resting on the toe support (Fig. 6), the wipers 20 may be manipulated in conjunction with the support to apply an updrafting, heightwise stress to the upper material, substantially perpendicular to the bottom.

65 By repeated manipulation of the wipers and support the upper material may be drawn taut and smooth over the last to eliminate all wrinkles and the lasting margin *m* caused to stand upwardly from the bottom. When the upper has been suitably stressed heightwise of the bottom the wipers are manipulated to move inwardly, parallel to the bottom, and in contact therewith, so as to fold the lasting margin over the shoul-

der and downwardly against the bottom while holding it under stress. As a preliminary to the inwiping operation the pulling over tacks at the toe may be removed and after several manipulations have been performed to draw the upper in to the satisfaction of the operator, the wipers are partially withdrawn, but without releasing the upper. As partially withheld they bear only against the upper at the shoulder, just below the plane of the bottom of the insole and thus hold the upper under stress while leaving the upstanding lasting margin free to be folded outwardly, as shown in Fig. 3, to expose the angle between the inner surface of the lasting margin and the edge of the insole. At this time if there is an excess of lasting margin, lining and/or counter material the excess may be trimmed off. With the upper material folded back a continuous ribbon of adhesive 24 substantially smaller in its cross-sectional dimensions than the height of the lasting margin *m* is applied directly in the angle which is represented at *a* in Fig. 4, around the entire end of the shoe. The wiping should be carried out as quickly as possible after applying the adhesive.

The ribbon of adhesive may be extruded from a nozzle 26 (Fig. 6) into the angle, the nozzle being connected to a pot 28, which is provided with heating means for liquifying the adhesive as it is required and which, together with the nozzle, is mounted on an arm 30, swingable on a suitable support 32 mounted on the frame of the toe laster for movement in a horizontal plane. The nozzle itself is preferably mounted on a flexible conductor so that it may be manipulated by the operator to follow the angle closely throughout changes in radius of the end. By using a slender nozzle, as illustrated, no heat is transmitted to the insole or upper, consequently there is very little danger that the adhesive, after it has been applied, will be kept soft and hence squeeze out as the margin is wiped inwardly by the wipers.

In lieu of a single nozzle and to effect a more uniform temperature condition in the applied ribbon of adhesive the latter may be applied by means of a pair of swivelly mounted nozzles 26a—26a, as shown in Fig. 7, which can be actuated to move from a spread apart position toward a common point or vice versa, as shown, to apply two symmetrically disposed ribbons starting at the tip and diverging rearwardly or starting at the sides and converging forwardly. The nozzles may be pivotally supported at the lower end of a suitable conductor 34, for supplying adhesive to them and have actuating links 36 connected to a common handle or other operating lever to effect their pivotal movement.

It may be desirable to use a crescent shaped nozzle 40, as shown in Fig. 8, having a narrow discharge slot 42 for applying the ribbon of adhesive throughout the entire length, from one side around the tip to the other side. The nozzle may be supplied at one or more points with adhesive through conductors 44 and a suitable check valve will be employed to cut off a finite ribbon as it is extruded. A thin narrow nozzle is employed so that it can be advanced close to the edge without touching the insole and hence without transferring heat thereto. Nozzles of different size will be made available, each of which is designed to be useful for shoes of two or three consecutive sizes.

Following disposition of the ribbon of adhesive in the angle the wipers 20 are again moved inwardly over the bottom so as to lay the lasting margin down against the bottom and to press it into intimate contact therewith. One or two passes of the wiper suffice, whereupon, the lasted shoe may be immediately removed without any waiting period for setting of the adhesive bond.

To be effective, as distinguished from prior practice, wherein the adhesive was applied with a brush or by spraying, the adhesive must be applied as a continuous ribbon around the entire toe or heel which is being lasted directly in the angle between the intersection of the inner surface of the upper and the upper surface of the insole

at the very edge. Preferably the ribbon should be of generally circular cross-section and have a diameter in the order of $\frac{1}{32}$ ", although it is to be understood that effective bonding can be obtained over a range of $\frac{1}{64}$ " to $\frac{1}{16}$ ". 5 If less than $\frac{1}{64}$ " there is an insufficient surface covering to produce the desired bond, and if more than $\frac{1}{16}$ ", much of it is squeezed out by pressure of the wipers so as to be objectionable. In Fig. 4 the disposition of the ribbon of adhesive is shown greatly enlarged with respect to the 10 parts of the shoe and in dotted lines there is shown what is believed to take place as the margin is laid down. The following action is predicated upon using a thermoplastic adhesive having a rather narrow range of liquid solid transition. In other words, the adhesive stays solid up to and within a very few degrees of its melting point and conversely solidifies very quickly upon cooling a few degrees from its melting point. Consequently, there is substantially no softening period and no chance for the adhesive bond to distort if held for a sufficient length of 15 time to permit its solidification. By choosing such an adhesive it is possible to apply it at a temperature close enough to its solidifying point so that the parts of the shoe to which it is applied immediately brings the adhesive down to a solidifying point, at least on its surface, 20 and within a few seconds after it touches the parts, thus forming a bond between the surface of the adhesive and the parts being joined which holds some of the adhesive in the corner, as shown in Fig. 4. As the wipers are brought inwardly however the still hot interior part of the adhesive ribbon is squeezed away from the corner and caused to roll forwardly between the closing angle, spreading over the surfaces as they come together and adhering thereto because it solidifies as fast as it comes in contact therewith, with very little danger of being squeezed out 25 from between the interfaces as has happened previously due to heating of the insole during the application of the adhesive.

Thus, by controlling the quantity and temperature of the adhesive, using a thermoplastic adhesive having a very 30 narrow range of solid to liquid phase, and starting its application at the corner so that it has a long path to cover before it reaches the edge of the margin, it is possible to produce a bond between the lasting margin and the insole which takes effect progressively as the lasting margin is laid down so that by the time the margin is fully laid down the bond is sufficiently strong to resist the retractive forces in the upper material. Accordingly, the completed shoe may be removed from the lasting machine at once without fear of the upper pulling back 35 because of weakness in the bond or fear of gradual creep or flow of the adhesive itself over a period of time so as to release the margin.

The following are three examples of adhesive of a character required to afford a satisfactory bond according 40 to the method of lasting described above.

Example 1

Versamid 930	83.3%
Versamid 100	16.7%
Melting point	105-115° C.
Viscosity	150 poises at 133° C.

Example 2

Versamid 940	75%
Pentalyn A	20%
Piccolastic A25	5%
Melting point	95-105° C.
Viscosity	150 poises at 120° C.

Example 3

Versamid 930	37.5%
Versamid 940	37.5%
Pentalyn A	20.0%
Piccolastic A25	5.0%
Melting point	95-105° C.
Viscosity	150 poises at 121° C.

The resins referred to in the foregoing examples are identified as follows:

Resin	Source	Chemical Composition
(1) Versamid 930-----	General Mills, Inc-----	Polyamide of dimerized vegetable oil fatty acid and polyamine.
(2) Versamid 940-----	do-----	Do.
(3) Versamid 100-----	do-----	Do.
(4) Pentalyn A-----	Hercules Powder Co-----	Pentaerythritol ester of wood rosin.
(5) Piccolastic A25-----	Pennsylvania Industrial Chemical Corp-----	Low molecular weight polymer of styrene or its homologues.

The completely lasted end of a shoe is shown in Fig. 5, and has been found to be so permanent in its character that it does not lose its effectiveness or allow the upper to lose its snugness even while the bottom is being hammered, leveled and subjected to roughing preparatory to attaching the outsole to the bottom.

It should be understood that the present disclosure is for the purpose of illustration only and that this invention includes all modifications and equivalents which fall within the scope of the appended claims.

I claim:

1. The method of lasting shoes wherein the upper and insole have been assembled on a last with a lasting margin at one end of the shoe extending upwardly from the insole, comprising, depositing a ribbon of adhesive proximate to the juncture of the margin and insole which is substantially smaller in its cross-sectional dimensions than the height of the lasting margin and wiping the lasting margin over the insole so that portions of the ribbon will travel from proximate to the juncture outwardly thereof between the insole and lasting margin and other portions of the ribbon will progressively be caused to adhere to the margin and the insole during this travel.

2. The method of lasting shoes wherein the upper and insole have been assembled on a last with a lasting margin at one end of the shoe extending upwardly from the insole, comprising, depositing a ribbon of adhesive proximate to the juncture of the margin and insole which is substantially smaller in its cross-sectional dimensions than the height of the lasting margin and wiping the lasting margin over the insole so that portions of the ribbon will be squeezed in the direction of the lasting stress ahead of the approaching surfaces of the margin and insole as they are brought together while leaving other portions of the ribbon adhering to the surfaces which have been brought into contact.

3. The method of lasting shoes wherein the upper and insole have been assembled on a last with a lasting margin at one end of the shoe extending upwardly from

the insole, comprising, depositing a ribbon of adhesive proximate to the juncture of the margin and insole which is substantially smaller in its cross-sectional dimensions than the height of the lasting margin and wiping the lasting margin over the insole so that as the ribbon is squeezed portions of it will roll along ahead of the lasting margin as successive portions of the margin are pressed into engagement with the insole, while other portions of the ribbon will remain adhering to the surfaces which have previously been brought into engagement.

4. The method of lasting shoes wherein the upper and insole have been assembled on a last with a lasting margin at one end of the shoe extending upwardly from the insole, comprising, depositing a ribbon of adhesive proximate to the juncture of the margin and insole which is substantially smaller in its cross-sectional dimensions than the height of the lasting margin but which contains enough adhesive per unit length to afford an adequate amount of adhesive for bonding the entire width of the margin to the insole without excess, and wiping the lasting margin inwardly over the insole and the ribbon resting thereon, so that the ribbon is caused to roll from proximate to the edge of the insole inwardly, leaving as it rolls layers of adhesive on the margin and insole which adhere thereto and to each other so as to bond the margin to the insole.

5. The method of lasting shoes wherein the upper and insole have been assembled on a last with a lasting margin at one end of the shoe extending upwardly from the insole, comprising, depositing a continuous ribbon of liquid thermoplastic adhesive smaller in its cross-sectional dimensions than the height of the lasting margin and having a narrow liquid to solid temperature range, proximate to the juncture of the lasting margin and insole at said end, the adhesive solidifying at least on its surface when deposited, and wiping the lasting margin over the insole so that portions of the ribbon will travel from proximate to the juncture outwardly thereof between the insole and lasting margin and other portions of the ribbon will progressively be caused to adhere to the insole and lasting margin during this travel.
